CLAIM

The ornamental design for a swivel rocker, as shown and described.

DESCRIPTION

FIG. 1 is a front elevational view of a swivel rocker embodying my new design.

FIG. 2 is a side elevational view thereof.

FIG. 3 is a rear elevational view thereof.

FIG. 4 is a top view thereof.

FIG. 5 is a side elevational view of a rocker embodying my new design.

The sides of the chair forms not shown are mirror images of the chair form shown in FIG. 2.

FIG. 1**FIG. 2****FIG. 3***FIG. 4**FIG. 5*
